UNITED STATES PATENT OFFICE.

ADOLPH L. DE LEEUW, OF CINCINNATI, OHIO.

VEHICLE-WHEEL.

1,104,479.

Specification of Letters Patent. Patented July 21, 1914.

Application filed October 19, 1910. Serial No. 587,859.

To all whom it may concern:

Be it known that I, ADOLPH L. DE LEEUW, a citizen of the United States, residing at Cincinnati, in the county of Hamilton and State of Ohio, have invented certain new and useful Improvements in Vehicle-Wheels, of which the following is a specification.

My invention relates to vehicle-wheels, and the object of my invention is to provide cushioning means for a vehicle-wheel comprising woven stretches of metal or spring material annularly arranged whose meshes are normally as close at the peripheral as they are at the inner face thereof; further, to provide cushioning means for a vehicle-wheel comprising a structure having crossing stretches of metal or spring-material, the normal shape of the said stretches being irregular helices of greater pitch at the peripheral than at the inner face of said structure and having the greater portion of the weight of said stretches adjacent said periphery; further, to provide a cushioning means for a vehicle-wheel comprising a tubular structure of woven stretches of metal or spring-material whose normal mesh is longer and narrower and of as small area at the peripheral as at the inner face of said structure; further, to provide cushioning means for a vehicle-wheel comprising a woven tubing the stretches whereof are normally laid in helical lines having greater pitch and compression at one side than at the opposite side thereof; and, further, to provide a vehicle-wheel embracing cushioning means comprising a woven tubing annularly arranged, the stretches whereof are laid in irregular helical lines which are closer and of greater pitch and formed with greater compression at the peripheral than at the inner face thereof.

My invention also proposes a weave of uniform wire yielding a torus providing a distribution of metal as dense at its tread as elsewhere and having the strands at the tread disposed at such an angle to the great circle of the torus as will obviate the necessity of spacing the strands farther apart than elsewhere.

A further object of my invention is to provide a woven tubing comprising resilient stretches to form the primary supporting part of the tubing and stretches which have less resilience than the primary supporting stretches; further, to provide a woven tubing comprising resilient stretches to form

the primary supporting part of the tubing and stretches which are of less resilience and of greater cross-sectional area than the primary supporting stretches; and, further, to provide a structure of the character mentioned with a covering forming intimate connection with the less resilient stretches which latter form a locking means about the primary resilient stretches for maintaining the covering in place.

The invention will be further readily understood from the following description and claims, and from the drawings, in which latter:

Figure 1 is a side elevation of a vehicle-wheel embracing my invention in its preferred form. Fig. 2 is an enlarged side elevation of the woven structure in its preferred form, partly broken away, part of the wires of the portion shown being also omitted to more clearly show the directions in which the wires extend. Fig. 3 is an inside elevation of the same, with the wires partly broken away. Fig. 4 is an outside elevation of the same, with the wires partly broken away. Fig. 5 is a cross-section of the same on the line $z-z$ of Fig. 2. Fig. 6 is a side elevation of the woven structure, shown provided with a covering, partly broken away. Fig. 7 is a cross-section of the latter, on the line $y-y$ of Fig. 6, shown mounted on a wheel, partly broken away. Fig. 8 is a perspective view, partly broken away, showing my improved device provided with an outer tread received about the cushioning structure. Fig. 9 is a side elevation of the tubular structure provided with primary resilient stretches and less resilient stretches. Fig. 10 is a detail of the same in section on the line $x-x$ of Fig. 9. Fig. 11 is a detail of the same in section on the line $w-w$ of Fig. 9. Fig. 12 is a detail of the same in section on the line $w-w$ of Fig. 9, but provided with a covering; and Fig. 13 is a cross-section of the same on the line $x-x$ of Fig. 9, partly broken away, provided with a covering, and shown as part of a wheel, partly broken away.

A represents a vehicle-wheel which may be of suitable size and relative dimensions for the purpose intended. It embraces a central supporting part, arranged to support the axle or supporting stem of the vehicle, which is shown as comprising a hub B, 110 spokes C, and a rim D.

E is a woven structure, which is formed

up of stretches of metal or spring-material which are suitably woven, being shown as composed of wires, which will be of suitable cross-sectional form and of uniform size throughout their length. These wires are preferably of spring metal having great resilience, being preferably woven into a tubular structure with a mesh sufficiently close elastically to resist the load upon the same.

5 In its preferred form it is annularly arranged about the central supporting part of the vehicle-wheel, and as shown the meshes of the structure are of smaller area at the peripheral face than at the inner face of the same, as will be readily seen by a comparison of Figs. 3 and 4. I accomplish this by providing a greater portion of the metal comprising the structure cross-sectionally adjacent the peripheral face than the inner face of the 10 same. For accomplishing this purpose, further, it is desirable that the stretches be arranged in helical manner about the axis of the tube, those portions of the helices adjacent the inner face of the structure being of less pitch than those portions adjacent the peripheral face of the structure, whereby the mesh adjacent the peripheral portion is longer (see Fig. 4) and narrower and of less area than the mesh adjacent the inner portion of the structure, (see Fig. 3), the stretches being arranged laterally so as to be separated by distances decreasing in increasing ratio from the inner face to the peripheral face of the structure (see Figs. 5 and 7), such distances being measured on a line at substantial right angles to the stretches.

15 As shown the wires 1 are wound to the right, and the wires 2 to the left, the wires 1 and 2 crossing each other at the points 3. The meshes of the wire, shown at 4, at and adjacent to the periphery of the structure, are shown smaller than the meshes, shown at 5, at and adjacent to the inner face of the 20 structure. These meshes are shown considerably larger than they are in practice, many of the wires being omitted for better illustration, as instanced particularly in Figs. 2, 3, 4, and 5.

25 The meshes 4 are longer and narrower than the meshes 5. The major axes of the meshes 4 preferably extend lengthwise of the tubing, while the major axes of the meshes 5 preferably extend crosswise of the tubing. The shape of the stretches is shown as of irregular helices of greater pitch at and adjacent to the peripheral than at and adjacent to the inner face of the structure, a greater portion of the weight of said 30 stretches being at the periphery than at the inner face of said structure. Instancing this feature of my invention, the dotted line *a* (see Fig. 2) may represent the center of weight or gravity of the tubing cross-sectionally of the same, which it will be noted

is outside the cross-sectional center of said tubing, represented by the dotted line *b*. The tubing is preferably woven in such manner that there is greater compression upon the weave of the stretches at one side than at the other side of the tubing, whereby when the force exerted in holding the tubing in the weaving operation is released, the tubing will arrange itself in curved or annular form, and the face having the greater compression thereon will form the peripheral face of said curved or annularly formed tubing. I do not herein claim the method of so weaving my improved construction, nor the mechanism employed, reserving these for other applications, herein showing, describing and claiming the article produced. Apparatus for carrying out the method above referred to and for producing the article herein described is made the subject matter of my co-pending application Serial No. 606,903, filed February 6th, 1911.

The woven structure may if desired and preferably does form the primary cushioning means of the vehicle-wheel. The woven structure may if desired be provided with a protective covering 6 suitably applied. If desired, further, an outer peripheral part 7 may be provided, which embraces the tread 8 of the vehicle-wheel, the woven structure 95 being received between said central supporting part and peripheral part of the wheel. I have shown the structure mentioned located adjacent to the periphery of the wheel, although it may be located nearer the axis 100 of the wheel, or may if desired serve as the tread of the wheel. If a peripheral part embodying the tread of the wheel is employed, it may be flexible or rigid as may be desired. The meeting ends of the stretches 105 may be connected in suitable manner as shown by the joints 10.

For supporting the tubular structure about the central supporting part, the rim D may be provided with an annular groove 11, having 110 annular flaring side walls 12, 13, one of which may be an integral part of the rim, and the other be on a ring-section 14 clamped to the main part of the rim by bolts 15 and nuts 16, the ring section being provided with 115 an annular rabbet 17, the annular walls of said rabbet forming shoulders against which the main part of said rim is received. If desired, further, the tubing may also comprise stretches of less resilience than the 120 stretches 1 and 2, a preferred form of which is shown in Figs. 9 to 13 inclusive. These stretches of less resilience are preferably of greater diameter or cross-sectional area than the stretches 1 and 2 of resilient material, 125 the latter being instanced as the stretches 1' and 2' in Figs. 9 to 13 inclusive. These stretches of less resistance are preferably of markedly less resilience than the stretches 1' and 2', and are preferably of substantially 130

no resilience. They may be of fibrous material or a substance which is preferably capable of being woven with substantially little resistance with the stretches of resilient material in the tubing.

When employing the stretches of less resilience, which may be termed the secondary stretches, the stretches of primary resilient material mentioned, instanced as the wires 1' and 2', preferably form the primary supporting part of the tubing, and the stretches of less resilient material form the primary contact portion or, if desired, the securing portion of the tubing, and for aiding in these functions the stretches of less resilient material are preferably of greater cross-sectional area or diameter than the cross-sectional area or diameter of the primary supporting stretches.

I have instanced the stretches of less resilient material at 21 and 22. The less resilient stretches are arranged to pass in and out among the primary resilient stretches so as to be bound therewith and be located thereby. The stretches 21 are shown wound to the right and the stretches 22 to the left. In weaving the tubing, when employing both characters of stretches, the primary resilient stretches and the less resilient stretches are preferably arranged side by side, with the meshes relatively arranged as hereinbefore more particularly explained with reference to Figs. 1 to 7 inclusive, with a closer weave at the peripheral portion than at the inner portion of the tubing. The two characters of stretches preferably have coincident crossing points as clearly shown in Fig. 9.

The tubing employing the primary resilient stretches and the less resilient stretches may be employed in the same relations as the tubing described as composed of the resilient stretches 1 and 2.

If it is desired to provide a covering when employing both characters of stretches, the covering, indicated at 23, is received about the tubing.

The covering is preferably of elastic material, for instance rubber or the like. Its response to pressures is liable to be along different lines than the lines of response to pressures of the primary resilient stretches of the tubing. If in securing the covering in place it were molded only about the primary resilient stretches, the joints between the covering and tubular structure might in course of time be severed as a result of the stresses respectively of the covering and primary resilient stretches acting along different lines which would result in a "creeping" of the covering upon the tubing. In order to avoid such "creeping," and to secure the covering to the tubing, the covering is caused to have close connection with those portions of the stretches of less elastic material which are received about the outer faces of the pri-

mary resilient stretches, as by being molded about the same as shown at 24. These portions of the stretches of less resilient material which are received about the inner faces of the primary resilient stretches thereby form loops about the primary supporting stretches which maintain the covering in place irrespective of the directions of the lines of stress in performing the cushioning function of the wheel. That is to say, the secondary stretches, which are preferably non-resilient or only slightly so, form tying means for binding the covering to the primary resilient stretches and in practice will yield locally to the stresses between the covering and the primary resilient structure without undue resistance, but securely binding the covering to the tubing.

Having thus fully described my invention, what I claim as new and desire to secure by Letters Patent is:

1. A torus of strands normally interweaving at a pitch progressively increasing from its innermost to its outermost periphery.
2. A resilient self-sustaining tire of spring wire strands each helically interweaving normally at a pitch progressively increasing from its innermost to its outermost periphery.
3. A wire fabric constituting a tire element and consisting of a plurality of wire strands normally interweaving right and left at a pitch progressively increasing from its lesser to its greater peripheral portions.
4. A torus of stiff resilient strands helically normally interweaving to form circumferentially elongated diamond-shaped meshes at its major periphery and transversely elongated diamond-shaped meshes at its minor periphery.
5. A woven wire fabric constituting a tire element and consisting of a plurality of spring wire strands interweaving right and left at a pitch progressively increasing from an inner peripheral line to its outermost peripheral portion, the meshes at the outermost peripheral portion being normally circumferentially elongated, those at an intermediate periphery being normally right-angled parallelograms, and those at an inner peripheral portion being normally transversely elongated.
6. A torus comprising a right and a left series of interweaving helical strands, the strands of each series increasing in pitch and being in parallelism from the innermost to the outermost periphery of said torus.
7. A torus of woven stiff spring-metal strands interweaving helically at a pitch increasing from the inner to the outer periphery thereof, the strands being crowded in closer relation to one another at the tread than at other portions of the torus.
8. A woven wire fabric constituting a tire element and consisting of a multiplicity of

- spring wire strands of uniform cross-section interweaving right and left at a pitch progressively increasing from an inner peripheral line to its outermost peripheral portion, said strands being crowded together as closely at the tread portion as elsewhere and providing as dense a distribution of metal per unit area at the said tread as at the innermost periphery.
- 10 9. A vehicle-wheel comprising a central supporting part and a structure received thereabout comprising woven helical stretches of spring-material having a mesh at the periphery thereof as small as at the inner face thereof, and forming cushioning means for said vehicle-wheel.
- 15 10. A vehicle-wheel comprising a central supporting part, a structure received thereabout comprising woven helical stretches of metal having as close a mesh at the periphery as at the inner face thereof, and a covering for said structure.
- 20 11. A vehicle-wheel comprising a central supporting part, and a structure received thereabout comprising woven stretches of metal in the form of irregular helices of greater pitch at the periphery than at the inner face thereof and cross-sectionally provided with a greater number of stretches at the peripheral than at the inner face of the same.
- 25 12. A vehicle-wheel comprising a central supporting part, a peripheral part, and a tubular structure comprising woven stretches of spring-material in the shape of irregular helices of greater pitch at the periphery than at the inner face of said tubular structure and cross-sectionally comprising a greater number of stretches at the peripheral than at the inner face of the same, for cross-sectionally providing greater weight of metal at the peripheral than at the inner face of said structure and providing said tubular structure with smaller mesh at the peripheral than at the inner face of same, said tubular structure received between said central supporting part and peripheral part and forming the primary cushioning means of said vehicle-wheel.
- 30 13. A cushioning means for a vehicle-wheel comprising a structure embracing woven helical stretches of spring-material having a mesh at the periphery thereof as small as at the inner face thereof.
- 35 14. A cushioning means for a vehicle-wheel comprising a structure embracing woven stretches of spring-material, helically arranged, said structure having a longitudinal axis which is curved, and the helices described by said stretches being of less pitch and forming larger sized meshes adjacent the inner face of said structure than adjacent the peripheral face of said structure.
- 40 15. A cushioning means for a vehicle-wheel comprising a curved tubing embracing woven stretches of spring-material arranged in irregular helices having less pitch adjacent the inner than the peripheral face of said tubing.
- 45 16. A cushioning means for a vehicle-wheel comprising a tubing annularly formed and embracing woven stretches of spring-material of uniform size helically arranged, the center of gravity of said tubing cross-sectionally of the same being outside the cross-sectional center of said tubing.
- 50 17. A cushioning means for a vehicle-wheel comprising an endless tubular structure annularly formed, embracing woven stretches of spring-material helically arranged with less pitch at the inner face and greater pitch at the peripheral face of said structure, and the mesh whereof is closer at said peripheral face than it is at the inner face of said structure.
- 55 18. A cushioning means for a vehicle-wheel comprising an annularly shaped tubing of woven stretches of metal in the form of irregular helices having the greater portions of their lengths outside the annular axis of said tubing.
- 60 19. A cushioning means for a vehicle-wheel comprising a curved woven tubing having helical stretches arranged with closer mesh at the peripheral than at the inner face thereof.
- 65 20. A cushioning means for a vehicle-wheel comprising a woven tubing of the character mentioned of stretches helically laid with greater pitch and less lateral distance and smaller mesh between said stretches at one side than at the other side of said tubing, for the purpose specified.
- 70 21. A vehicle-wheel comprising a central supporting part and a structure received thereabout comprising woven primary stretches of spring-material and stretches of less resilient material having a mesh at the periphery thereof as small as at the inner face thereof, and forming cushioning means for said vehicle-wheel.
- 75 22. A cushioning means for a vehicle-wheel comprising a curved tubing embracing woven primary stretches of spring-material and secondary stretches of less resilient material, said woven primary stretches of spring-material arranged in irregular helices having less pitch adjacent the inner than the peripheral face of said tubing.
- 80 23. A cushioning means for a vehicle-wheel comprising a curved tubing embracing woven primary stretches of spring-material and secondary stretches of less resilient material, said woven primary stretches of spring-material arranged in irregular helices having less pitch adjacent the inner than the peripheral face of said tubing.

tubing, and said secondary stretches being respectively of larger size than said primary stretches.

24. A cushioning means for a vehicle-wheel comprising a curved tubing embracing woven primary stretches of spring-material and secondary stretches of less resilient material, said primary stretches of spring-material arranged in irregular helices having less pitch adjacent the inner than the peripheral face of said tubing, and forming the primary supporting part of said curved tubing, and said secondary stretches of less resilient material forming separating means between said primary stretches.

25. A curved woven cushioning means for a vehicle-wheel comprising in combination primary stretches of spring-material and secondary stretches of less resilient material arranged more compactly at the peripheral than at the inner face thereof, the said secondary stretches being of larger size than said primary stretches, for the purpose described.

26. A curved woven tubing of the character mentioned of resilient stretches helically laid with greater pitch at the peripheral than at the inner face thereof, and less resilient stretches, and a covering secured to said less resilient stretches, which latter have portions of their strands received about said first-named resilient stretches inside said tubing.

27. A curved woven tubing of the character mentioned of resilient stretches helically laid with greater pitch at the peripheral than at the inner face thereof and less resilient stretches, and a covering secured to said less resilient stretches, which latter have portions of their strands received about said first-named resilient stretches inside said tubing, said less resilient stretches being of larger size than said resilient stretches.

28. A cushioning means for a vehicle-wheel comprising a curved woven tubing of the character mentioned of primary resilient and less resilient stretches of uniform

size throughout their length and helically laid with greater amount of material at the peripheral than at the inner face thereof.

29. A cushioning means for a vehicle-wheel comprising a curved woven tubing of the character mentioned of primary resilient and less resilient stretches helically laid with greater amount of material at the peripheral than at the inner face thereof, said less resilient stretches being laid alternately inside and outside said primary resilient stretches and being of larger size than said resilient stretches.

30. A curved woven tubing of the character mentioned of primary resilient and less resilient stretches helically laid with greater amount of material at the peripheral than at the inner face thereof, said less resilient stretches being laid alternately inside and outside said resilient stretches and being of greater diameters than said resilient stretches, and a covering connecting with the outside portions of said less resilient stretches.

31. A cushioning means for a vehicle-wheel comprising a woven tubing of the character mentioned, formed of helical stretches of uniform size, said stretches being so laid that there is a greater weight of material on one side of a plane passing through the axis of said tubing than on the other side thereof.

32. A cushioning means for a vehicle-wheel comprising an annular woven tubing of the character mentioned, formed of helical stretches of uniform size, said stretches being so laid that there is a greater weight of material outside of any line passing through the axis of the tubing perpendicular to the plane of the annulus than on the inside of such line.

In testimony whereof, I have signed my name hereto in the presence of two subscribing witnesses.

ADOLPH L. DE LEEUW.
